SIMULATED LOUVERED SHUTTER
 Math W. Rauen, Oconomowoc, Wis., assignor to Lyf-Alum, Inc., Oconomowoc, Wis., a corporation of Wisconsin

Filed Jan. 3, 1961, Ser. No. 80,249

1 Claim. (Cl. 20—63)

This invention relates to a simulated decorative louvered shutter.

It is an objective of the invention to provide an improved simulated shutter which is adjustable in length to fit any requirement but is exceptionally rigid when assembled. Previously known simulated shutters made of wood must be made and stocked in a variety of sizes to conform to the height of the windows with which they are used. By making the shutter in two or more sections fabricated of thin sheet metal such as aluminum, it is possible to produce a simulated shutter which will serve all practical needs. The present shutter is an improvement over all simulated shutters heretofore proposed in that its complementary parts interlock in all positions to which they may be adjusted and, in addition, may be nested for transportation and storage. Not only does the interlock contribute greatly to the strength of a shutter made of thin and relatively flexible material such as aluminum, but the cross section of the product is also a factor in making it rigid in use.

In the drawings:

FIG. 1 is a front elevational view of a simulated shutter embodying the invention, portions being broken away.

FIG. 2 is an enlarged fragmentary detail view in perspective showing the manner in which the component parts of the simulated shutter are interlocked in use.

FIG. 3 is a fragmentary front elevational view of an extension unit which may be employed when needed.

FIG. 4 is a fragmentary rear elevational view of the lower extremity of the uppermost section of the simulated shutter.

The upper element A comprises left and right side portions 6 and 7 and a top portion 8 which simulate corresponding portions of a sash. Each of the sash-simulating portions 6, 7 and 8 is provided with a marginal flange as shown respectively at 9, 10 and 11. The flanges represent the outside edges of the simulated sash.

The inside edges of the simulated sash are represented by the beveled or inclined surfaces 12, 13 and 14, respectively, these being of less depth from front to rear than the flanges 9, 10 and 11. Integral with the inclined portions 12, 13 and 14 are the strips 15, 16 and 17 which border the louvers at the sides and the top of the section A.

Each of the louvers 20 has a flat top portion 21 in a plane which is parallel to but offset from the front surfaces 6, 7 and 8 which simulate the sash. The panel portion 22 of each louver is inclined downwardly and forwardly so that its lower margin 23 is substantially flush with the flat border strips 15 and 16 at each side of the unit. An end wall 24 connects each louver integrally with the border strip 16 at one side and the border strip 15 at the other, the entire unit being stamped in one piece.

The lower unit B, likewise stamped in one piece, is similar to unit A except that it includes a bottom sash-simulating section 25 which is sufficiently narrower than the sash simulating section 8 at the top of unit A so that the side simulating sections 26 and 27 fit within the side simulating sections 6 and 7 of unit A, the difference in width being only equal to the thickness of the metal flanges at the sides of the simulated shutters. Of course, it is understood that the upper section A lacks any simulated bottom sash member and the lower section B lacks any simulated top sash member. An important feature

2

of the invention is the provision on the lowermost louver 20 of the upper unit A of a reversely bent flange 28 which engages the lower margin 23 of one of the louvers 22 of the lower section B when the two sections are assembled as shown in FIG. 2.

In order to adapt the device for use with windows of a height greater than the height to which the sections A and B can be extended, a third section C is provided as shown in FIG. 3. This section has a reversely hooked flange 28 on its lowest louver but it has neither a top sash simulating portion nor a simulated bottom sash portion. Its simulated side sash portions 30 and 31 are at a spacing which may be intermediate that of the simulated side sash portions of sections A and B. The metal used is so thin and the deflection required is so slight that it is readily possible to position the insert section C between the flanges of section A and outside of the flanges of section B.

Each of the sections A and B is provided with screw holes 32 at the corners of its simulated sash portions. Section A is provided additionally with screw holes at 33 for which there is no counterpart in member B as manufactured. It is intended that suitable registering holes will be provided in member B at the time the sections are assembled. The screws are primarily for the purpose of mounting the simulated shutters on the wall of a building but they perform the further function of holding the two simulated sections together.

It will be noted that even without the screws 34 the simulated shutter sections are securely interlocked not alone by the hook flange 28 but by the interlocking engagement of the louvers in the lapping portions of the respective units. Referring to the lower part of FIG. 2, wherein the lap is illustrated, it will be observed that the flat portions 21 and the inclined panels 22 of the respective louvers are in face contact throughout. The lower margins 35 of the louvers of section B rest upon the top margins 36 of the side panels 24 of section A, the angle of inclination being such that each of the lower margins 40 of the louvers of the top section is securely wedged into an angle from which it cannot escape without longitudinal displacement of the respective sections. Accordingly, if the sections are anchored at their remote corners against such displacement, they must necessarily remain securely locked together. The same type of interlock is effective between the inserted section C and upper and lower sections A and B when the inserted section is used.

Due to the integral stamping of the units to provide the relatively deep section and oblique louvers as shown, the units are rigid to an extent which permits making them of very light-weight material and eliminates any necessity of internal bracing of any sort. The absence of internal bracing permits of the nesting of the units A and B, the lower unit B being inverted and slipped into the unit A in its inverted position as shown in FIG. 5. This greatly reduces the cost of packaging, shipping and storing the units.

I claim:

- A simulated shutter comprising the overlapped assembly of
- prefabricated separately incomplete shutter units,
  - each comprising integrally prefabricated sash and louver portions,
  - a part of one unit overlapping a part of the other unit and being longitudinally adjustable with respect to one another in a direction transverse to said louvers to adjust the overall length of the assembly,
  - the louvers of each unit extending to the overlapped ends thereof,
  - the exposed ends of said units respectively having top and bottom sash portions beyond said louvers,

- (f) and means for interlocking said units in any one of a plurality of overlapping positions in which all of the louvers in the overlapping part of one unit register in face contact with corresponding louvers in the overlapping part of the other unit,
- (g) whereby the overlapped assembly of said units simulates a single unitary shutter with evenly spaced louvers, regardless of the degree of overlap of the respective units,
- (h) each louver of one unit having a flange integrally connecting its end with a sash portion of said one unit,
- (i) said flange having an edge transverse to the edge of the corresponding louver of the other unit,
- (j) said flange edge and louver edge abutting to define registration of said louvers, at least one louver of

5

one unit having a marginal hook flange engaged in the assembly of said units with a corresponding margin of a louver of the other unit.
